UNITED STATES PATENT OFFICE.

FRANK B. TWINING, OF TROY, NEW YORK, ASSIGNOR TO GEO. P. IDE & COMPANY, INC.,
OF TROY, NEW YORK, A CORPORATION OF NEW YORK.

SOFT TURNDOWN COLLAR.

1,416,534.

Specification of Letters Patent. Patented May 16, 1922.

Application filed August 19, 1921. Serial No. 493,561.

To all whom it may concern:

Be it known that I, FRANK B. TWINING, a citizen of the United States, residing at Troy, in the county of Rensselaer, State of New York, have invented certain new and useful Improvements in Soft Turndown Collars, of which the following is a specification.

It has been the practice to make men's 10 collars and cuffs of a plurality of separate independent plies of material and stitch these plies together at their edges.

The object of my invention is to provide a soft turn down collar or cuff of multiply 15 interwoven fabric having an increased cross sectional area on each side of the fold line of the collar.

Another object of my invention is to reduce appreciably the number of operations 20 to produce a collar.

A further object of my invention is to produce a soft fold over collar of a single piece of multiply interwoven fabric of appropriate thickness and stiffness.

25 My invention consists of a soft folding collar made from one piece of multiply interwoven fabric, having a plurality of additional interwoven plies on each side of the folding line of the collar.

30 My invention consists wholly of a collar, cuff and the like made from a multiply interwoven fabric of uniform thickness throughout, having a thickened integral portion at the top of the neck band and at the 35 top of the rolled over top portion.

While I have, for the purpose of illustrating my invention shown and embodied only a soft turn down collar, it is of course understood that the invention is equally efficient in the manufacture of cuffs or especially soft cuffs.

I do not herein claim the fabric inasmuch as it forms the subject matter of another application to be filed by me August 19, 1921,

45 Serial No. 493,562.

In the drawing:

Figure 1 is a plan view of a soft fold collar laid out flat.

Figure 2 is a sectional view of the line 50 2—2 with the collar in its folded position.

As above stated, the collar is made from multiply interwoven fabric in a single piece, having the neck band 1, and the fold over top portion 2.

55 The neck band and fold over top portion are each provided with a thickened zone 3

and 4, extending the entire length of the collar, that portion of the fabric between the thickened zones 3 and 4 being of the same thickness as the fabric in the neck band and 60 the fold over top portion. All of the portions being integral and formed in the process of weaving the fabric.

This thickened portion may be obtained or produced by increasing the number of 65 threads in the zones 3 and 4, so that the zones 3 and 4 have a greater number of interwoven plies than the balance of the fabric in the collar.

The spacing of these thickened portions 70 3 and 4 cause the collar to naturally fold on a line between them.

In addition to the fold guiding function of the thickened portion of the collar, these portions increase, more or less, the rigidity 75 of the collar at the folding line, thereby holding the collar in a graceful and unbroken curve around the neck of the wearer.

Another function of these thickened portions is that when the collar is folded for 80 wear, the thickened portions are in close proximity one with the other, thereby forming a stop at the top of the collar between the neck band and the fold over top portion, which stop materially prevents the 85 necktie from wedging at the fold of the collar, so that the top edge of the necktie is always spaced below the folded line of the collar whereby the necktie may freely slide back and forth in the collar in the process 90 of tying the tie.

My improved collar has all of the advantages of soft and starched collars, plus the advantages resulting from my invention, among which may be mentioned that the collar stands up well without starching, is comparatively stiff and is free from wrinkling and the thickened portions constitute a predetermined fold line whereby the collar will always have a proper set on the neck of the 100 wearer without starching, besides which the thickened portions prevent the necktie from wedging in the collar.

What I claim is:

1. A folding collar or cuff, woven in one 105 piece, made up of a neck band and a top portion and a thickened portion on each side of the folding line of the collar defining the folding line.

2. A folding or turn down collar comprising 110 a neck band and a fold over top portion composed of a plurality of interwoven plies,

there being additional interwoven plies constituting a thickened portion on each side of the fold line of the collar.

3. A folding or turn down soft collar having a neck band and a top portion made of multiply interwoven fabric, one or more added interwoven plies at substantially the top of the neck band and at the top of the fold over top portion, to provide an increased integral thickness and stiffness at each side of the folding line of the collar.

4. A folding collar having a neck band portion and a fold over top portion of a thickness to impart stiffness to the collar, the neck band and the fold over top portion having an integral upper edge relatively stiffer than the other portion of the neck band and fold over top portion.

5. A folding collar or cuff woven in one piece made up of a neck band portion, and a top portion of uniform weave throughout its entire area, and an integrally woven strengthened fold guiding portion adjacent to and on each side of the fold line of the article.

6. A folding or turned down collar comprising a neck band and a fold over top portion, and composed of a plurality of interwoven layers or plies, one of said plies having additional threads woven therein to increase the thickness thereof adjacent to and on each side of the fold line of the collar to define the fold line of the collar.

In testimony whereof I affix my signature.

FRANK B. TWINING.
